SETTING MECHANISM FOR PREDETERMINING COUNTERS

William F. Berck, Oakland, Calif., assignor to
Ralph N. Brodie Company, Oakland, Calif., a
corporation of California

Application January 21, 1937, Serial No. 121,445

7 Claims. (Cl. 235—117)

This invention relates to counter mechanisms for use in connection with liquid meters and like devices.

In a copending application entitled "Automatic shut off mechanism for liquid meters", filed May 13, 1935, bearing Serial No. 21,197, I have disclosed a mechanism for automatically closing a liquid meter shut-off valve after a predetermined volume of liquid has passed through the meter with 5 which the valve is associated. This automatic mechanism is controlled by a counter mechanism operated by the meter, the setting of which counter mechanism determines the amount of liquid which will be discharged through the meter before the valve is closed. This counter mechanism includes a selected number of counter wheels 10 associated in the usual fashion so that they will operate to indicate units, tens and hundreds. For setting this predetermining counter, I have 20 shown in the above-identified application each counter wheel fitted with a separate operating member.

In a second copending application entitled "Setting mechanism for predetermining counters", filed May 13, 1935, bearing Serial No. 21,196, I have shown an improved construction of such predetermining counter mechanisms wherein the setting of all the counter wheels 25 may be effected by manipulation of a single operating member. In this mechanism the counter wheel was selected for setting by shifting the operating member coaxially with respect to the wheels and then turning the same to set the counter wheel so selected.

It is the principal object of my present invention to improve and simplify the construction and 30 operation of predetermining counters of the character referred to whereby I am enabled to produce such a device wherein the counter wheels may be 35 selectively engaged and set by simply revolving a single operating member.

One form which the invention may assume is exemplified in the following description and 40 illustrated by way of example in the accompanying drawings, in which:

Fig. 1 is a perspective view of a predetermining counter mechanism embodying the preferred form 45 of my invention.

Fig. 2 is a view in longitudinal section there- 50 through showing the operating member in position to operate the units wheel.

Fig. 3 is a similar view showing the operating member in position to set the tens wheel.

Fig. 4 is a similar view showing the operating 55 member in position to set the hundreds wheel.

Fig. 5 is a transverse sectional view taken on line V—V of Fig. 2.

Fig. 6 is a similar transverse section showing merely the counter wheel but disclosing the manner in which the pawl is rendered ineffective 5 when this counter wheel is not selected for operation.

Fig. 7 is a perspective view of the actuating shaft.

Fig. 8 is a perspective view of the sleeve in 10 which the actuating member is mounted.

Fig. 9 is a transverse sectional view taken on line IX—IX of Fig. 3.

Fig. 10 is a transverse sectional view taken on line X—X of Fig. 2.

Fig. 11 is a transverse sectional view taken on line XI—XI of Fig. 2.

Referring more particularly to the accompanying drawings, I there illustrate what I prefer to term a predetermining counter 10. This counter includes a units wheel 11, a tens wheel 12 and a hundreds wheel 14. The units wheel 11 is driven by a worm gear 15 which is driven by the meter through the medium of a worm 16. The counter wheels 11, 12 and 14 are operatively 20 associated as in standard practice by mutilated gears and pinions so that upon each revolution of the units wheel 11, the tens wheel revolves 25 one-tenth of a revolution, and upon each complete revolution of the tens wheel, the hundreds 30 wheel 14 revolves one-tenth of a revolution.

For this purpose a pinion shaft 17 is provided on which is mounted a pinion 18 for driving the tens wheel 12 and a pinion 19 for driving the hundreds wheel 14. The units wheel 11 is fitted 35 with a mutilated gear 20 to mesh with and drive the pinion 18, and the tens wheel 12 is fitted with a mutilated gear 21 to mesh with and drive the pinion 19. The pinion 18 is in mesh with a gear 22 on the adjacent tens wheel, and the pinion 19 is in mesh with a gear 23 on the adjacent 40 hundreds wheel. The ratio is such that the units wheel 11 will intermittently drive the gear 22 one-tenth of a revolution each time the units wheel completes one revolution, and the tens 45 wheel will intermittently drive the gear 23 one-tenth of a revolution each time the tens wheel completes one revolution. The gears 22 and 23 are connected to the tens and hundreds wheels, respectively, through a ratchet mechanism dis- 50 closed in Figs. 3 and 9.

From these figures it will be seen that the tens and hundreds wheels are each fitted with an internal ratchet wheel 24 engageable by pivotal pawls 25 carried by the gears 22 and 23. The 55

engagement is such that rotation in one direction by the gears 22 and 23 will drive the wheels 12 and 14, and thus the latter wheels are free to be turned in the same direction. This, of course, 5 permits setting thereof and it is to be understood that the direction referred to is counterclockwise as the parts are viewed looking from left to right in Figure 1 and as they appear in Figures 5 and 6. This same relation between directions 10 of rotation will hereinafter be adhered to, and it must not be lost sight of that Figures 10 and 11 view the parts from right to left as indicated by the arrows of the section lines X-X and XI-XI of Figure 2, and thus opposite to Figures 5 and 6. 15 The units wheel 11 is likewise fitted with a similar ratchet wheel 26 engaged by pawls 27 carried by a disk 28, which disk is driven by the worm gear 15 as shown in Fig. 3.

The predetermined counter here disclosed (as 20 shown and described in my copending application Ser. No. 21,197 previously referred to) is intended to be utilized to indicate the volume of liquid it is desired to discharge through the meter with which it is associated. For example, should 25 the volume desired be 125 gallons, the units wheel is set at 5, the tens wheel is set at 2 and the hundred wheel is set at 1. When the meter commences operating, these counter wheels retrograde toward zero, and when all three reach zero, 30 they operate a trip mechanism which causes closing of the meter shut-off valve, thus stopping the meter. For this purpose the three counter wheels are each fitted with a trip member 29 relatively associated with a valve trip 35 mechanism not illustrated. It is believed unnecessary to go into the description of the tripping operation here inasmuch as the present invention relates solely to the means of presetting the counter wheels 11, 12 and 14 prior to the operation 40 of the meter.

Reference being had to the accompanying drawings, it will be seen that the counter mechanism is mounted in a frame which includes upright members 30, 31 and 32. Journalled in the 45 upright members 30 and 31 is a tubular shield or sleeve 33 in which is rotatably disposed an actuating spindle 34. At its innermost end this spindle is journalled in the worm gear 15, the shaft of which is journalled in the upright member 32. Mounted on the outer end of this actuating spindle so as to be non-rotatable with respect thereto is an operating knob 35. By turning this knob the actuating spindle 34 may be revolved.

55 It is essential that the sleeve or shield 33 be prevented from rotation in a clockwise direction viewing the parts as in Figures 5 and 6 as above stated and for this reason keyed on the sleeve is a ratchet wheel 36, which ratchet wheel 60 cooperates with a spring-pressed dog 37 carried by the frame adjacent the upright member 30 thereof. This spring-pressed dog 37 permits the ratchet wheel and the sleeve 33 to which it is 65 keyed to revolve in a counter-clockwise direction but not in a clockwise direction. It should be stated that the operating knob 35 is so mounted on the sleeve 33 that it and the actuating spindle 34 may revolve relative to the sleeve in a clockwise fashion but will be latched to the sleeve so as to revolve in a counter-clockwise direction therewith. That is to say, when the operating knob 35 is revolved in a clockwise direction, it 70 and the actuating spindle 34 revolve relative to 75 the sleeve 33, but when the knob 35 is turned

in a counter-clockwise direction, it and the spindle 34 and the sleeve 33 revolve in unison.

The purpose of permitting the spindle 34 to revolve in a clockwise direction relative to the sleeve is to enable the selection of one of the 5 counter wheels for turning. For this purpose each counter wheel is provided with a spring-pressed pawl 38 as illustrated in Figs. 5 and 6, and when the wheels are all set at zero, the pawls 38 of the three counter wheels 11, 12 and 14 are 10 in alignment. In register with each pawl 38, the sleeve 33 is formed with a circumferential slot 39 through which the pawls 38 project to engage the periphery of the actuating spindle 34.

The spindle 34 has three pawl-engaging 15 notches 40, 41 and 42 in its peripheral surface which are circumferentially spaced apart ninety degrees and while these notches are disposed longitudinally of the spindle to register with the slots 39 of the sleeve 33, it is obvious that, owing 20 to their circumferential spacing, when one of the notches of the spindle is registered with one of the slots 39, the other two notches will be shielded by the sleeve 33.

From Figs. 5 and 6 it will be noticed that the 25 notches 40, 41 and 42 of the actuating spindle are formed by the use of an end mill so that rotation of the actuating spindle 34 in a counter-clockwise direction will so engage the proper pawl 38 that rotation of the actuating spindle 34 will 30 be accompanied by rotation of the selected counter wheel, but that the rotation of the actuating spindle 34 in a clockwise direction will be ineffective to turn the counter wheels.

To latch the knob 35, the spindle 34 and the 35 sleeve 33 together, when the knob is turned in a counter-clockwise direction for setting the counter wheels, the outer end of the sleeve 33 is formed with three slots 43, 44 and 45, which are spaced ninety degrees apart. For cooperation with these slots, the knob 35 is provided with a spring-pressed pawl 46, so mounted that when engaged with one of the slots 43, 44 and 45 and the knob 35 is turned counter-clockwise, the sleeve 33 will be turned in unison with the 45 knob. When the knob 35 is turned in a clockwise direction, the pawl 46 is ineffective to impart rotation to the sleeve 33. The pawl 46 will be in register with the slot 43 of the sleeve when the notch 42 is in register with the respective 50 slot 39 of sleeve 33 to receive the pawl 38 of the units wheel 11 at zero position of the latter. When the knob and spindle 34 are turned to place the notch 41 in the spindle 34 in register with the pawl 38 of the tens wheel 12, the pawl 55 46 of the knob will be in register with the slot 44 of the sleeve 33. When the notch 40 is in register with the pawl 38 of the hundreds wheel, the pawl 46 of the knob will be in register with the slot 45 in the sleeve 33.

Consequently, when the pawl is engaged with the slot 43 and is turned in a counter-clockwise direction, the knob 35, the spindle 34, the sleeve 33 and the units wheel 11 will turn in unison so that the units wheel may be set to any reading. When the knob pawl 46 is engaged with the slot 44 in the sleeve, the spindle 34 will be positioned to position the notch 41 in the spindle in latching register with the pawl 38 of the tens wheel 12, and upon subsequent rotation in a 60 counter-clockwise direction of the knob 35, the knob, the sleeve 33, the spindle 34 and the tens wheel 12 will be revolved in unison so as to set the tens wheel. If the knob is then turned in a clockwise direction to register its pawl 46 with 65 70 75 70 75 75

the slot 45, the spindle 34 will be turned to register the notch 4 with the pawl 38 of the hundreds wheel 14 so that upon subsequent rotation of the knob 35 in a counter-clockwise direction, the knob 35, the spindle 34, the sleeve 33 and the hundreds wheel 14 will be turned in unison to set the latter to any desired reading.

In order that the operator may determine the relative position of the spindle with respect to the sleeve and counter wheels, I have provided a slot 47 in the inner end of the sleeve 33, which slot is adapted to be engaged by a spring-pressed ball 48 carried by the spindle 34 when the notch 42 in the spindle is in register with the pawl 38 of the units wheel 11. If it is desired to operate the device, the operator turns the knob in a clockwise direction until he is sensibly aware of the engagement of the ball 48 with the slot 47. This informs him that the notch 42 is in register with the pawl 38 of the units wheel 11 and that the knob pawl 46 is in register with the slot 43 of the sleeve 33. This gives the operator a starting point in setting or presetting the counter mechanism.

In operation of the device, it is constructed and assembled substantially as illustrated in the drawings and operatively associated with the meter, and if it is a quantity controlled device, it is operatively associated with the shut-off valve trip mechanism of the meter.

Assuming that all of the counter wheels indicate zero, as they are numbered in standard practice, and it is desired to have the meter discharge say 125 gallons, the actuating spindle 34 is turned in a clockwise direction by applying a turning movement to the knob 35 until the ball 48 engages the slot 47 in the sleeve 33. The operator will feel this engagement inasmuch as it takes some force to overcome this engagement. Immediately that he feels this engagement, he is made aware that the notch 42 in the actuating spindle 34 is in register with the proper slot in the sleeve 33 and with the pawl 38 of the units wheel 11. By turning the knob 35 in a counter-clockwise direction, the counter wheel may be turned until it indicates the numeral 5. The knob 35 is then turned in a clockwise direction, during which movement the sleeve 33 will remain stationary due to the provision of the ratchet wheel 36 and dog 37. By turning the actuating spindle 34 in a clockwise direction, the notch 42 is turned out of register with the pawl 38 of the units wheel 11, and when it is turned ninety degrees, it places the notch 41 in the actuating spindle into register with the proper slot in the sleeve 33 and with the pawl 38 of the tens wheel 12. At the same time this places the knob pawl 46 into register with the slot 44 in the sleeve, and upon subsequent rotation of the knob in a counter-clockwise direction the tens wheel will be rotated sufficiently to set it so that it places the numeral 2 thereof in indicating position. The knob 35 is then turned to turn the spindle 34 in a clockwise direction for at least ninety degrees to place the notch 41 out of register with the pawl 38 of the tens wheel 12 and to place the notch 40 in register with the pawl 38 of the hundreds wheel 14. The knob 35 is then turned in a counter-clockwise direction sufficiently to set it so that the numeral 1 thereon is in indicating position. After this setting, the meter shut-off valve is opened so that the meter may commence operating.

Operation of the meter will be accompanied by operation of the worm gear drive 15 which will

in turn properly drive the counter wheels 11, 12 and 14 as previously described. These wheels will be driven in the direction of the arrow in Fig. 5 and will retrograde toward zero. When the zeros on the three wheels all align with the indicating position, the trip member 29 of these wheels will cause tripping of the shut-off valve to close the same and shut off the meter.

From the foregoing it is obvious that I have provided an improved and simplified setting mechanism for counters, by means of which mechanism the counter may be set by simply revolving a single knob or operating member.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A device of the character described comprising a rotatable actuating member, a plurality of rotatable elements rotatably mounted about the axis of said member, and complementary means on said elements and said member whereby the latter may be set by rotation in one direction to selectively engage any one of said elements to adjust the position of the selected element by rotation of said member in the opposite direction.

2. A device of the character described comprising a plurality of rotatable elements, an operating member extending coaxially therethrough and freely rotatable in one direction in respect thereto, cooperating ratchet means on said member and on each of said elements and capable of selection by rotation of said member in the aforesaid direction, said ratchet means forming a driving connection between said member and the selected element operable to adjust the said element upon movement of the said operating member in the opposite direction of rotation.

3. A device of the character described comprising a plurality of rotatable elements, an operating member extending coaxially therethrough and capable of rotation relative thereto in one direction, cooperating ratchet means between said member and each of said elements and capable of being successively rendered effective by rotation of said member in the same direction, said ratchet means effective to adjustably shift the selected element upon rotation of said member in the opposite direction.

4. A device of the character described comprising a plurality of counter wheels, an actuating member extending coaxially therethrough, a pawl carried by each wheel, said member being formed with means adapted to be selectively placed in register with the pawl of a selected wheel upon rotation of said member in one direction, the pawl of the selected wheel and the means on said member forming a driving connection between the two when the member is turned in the other direction.

5. A device of the character described comprising a plurality of counter wheels, an actuating member extending coaxially therethrough, a pawl carried by each wheel, said actuating member having a socket to register with each pawl, said sockets being relatively differently positioned about the circumference of said member and so formed whereby they may be independently and successively brought into register with the pawl of a selected wheel by rotation of said member

65

70

75

75

in one direction, and the pawl of the selected wheel will be engaged by the cooperating socket when the member is turned in the opposite direction.

5 6. A device of the character described comprising a rotatably supported spindle held against endwise movement, a sleeve mounted on said spindle, a plurality of rotatable elements rotatably mounted on said sleeve, a spring-pressed pawl on each element, said sleeve having a circumferential slot for each pawl and normally in register therewith, said spindle being formed with a series of circumferentially spaced notches, one notch for each pawl, the circumferential spacing between said notches being such that only one thereof may register with a slot in the sleeve at one time, the relation of the notches and pawls being such as to form a driving connection between the selected notch and the pawl of the selected element when said spindle is rotated in one direction and to be ineffective when said spindle is revolved in the opposite direction.

7. A device of the character described compris-

5
10
15
20

ing a rotatably supported spindle held against endwise movement, a sleeve mounted on said spindle, a plurality of rotatable elements rotatably mounted on said sleeve, a spring-pressed pawl on each element, said sleeve having a circumferential slot for each pawl and in register therewith, said spindle being formed with a series of circumferentially spaced notches, one notch for each pawl, the circumferential spacing between said notches being such that only one thereof may register with a slot in the sleeve at one time, the relation of the notches and pawls being such as to form a driving connection between the selected notch and the pawl of the selected element when said spindle is rotated in one direction and to be ineffective when said spindle is revolved in the opposite direction, connections between said spindle and said sleeve constraining said sleeve to revolve together with said spindle in the first-named direction, and means holding said sleeve against rotation in the opposite direction.

WILLIAM F. BERCK.
